DESIGN FOR A SLEEVE STEAMER

Raymond J. Gabler, Kansas City, Mo., assignor
to Butler Manufacturing Company, Kansas
City, Mo., a corporation of Missouri

Application February 3, 1940, Serial No. 89,989

Term of patent 14 years

To all whom it may concern:

Be it known that I, Raymond J. Gabler, a citizen of the United States, residing at Kansas City, in the county of Jackson and State of Missouri, have invented a new, original, and ornamental Design for a Sleeve Steamer, of which the following is a specification, reference being had to the accompanying drawing, forming part thereof, in which,

Figure 1 is a perspective view of a sleeve steamer showing my new design.

Figure 2 is a side elevational view of the sleeve steamer shown in Figure 1.

Figure 3 is a top plan view of the sleeve steamer shown in Figure 1.

I claim:

The ornamental design for a sleeve steamer, substantially as shown.

RAYMOND J. GABLER.
